US00D502938S

(12) **United States Design Patent** (10) Patent No.: **US D502,938 S**
Tokioka et al. (45) Date of Patent: **** Mar. 15, 2005**

(54) **HEADPHONES FOR PORTABLE AUDIO DEVICES**

(75) Inventors: **Eigo Tokioka, Nishinomiya (JP); Kazuhiko Shibata, Kyotanabe (JP)**

(73) Assignee: **Matsushita Electric Industrial Co., Ltd., Osaka (JP)**

(**) Term: **14 Years**

(21) Appl. No.: **29/201,159**

(22) Filed: **Mar. 11, 2004**

(30) **Foreign Application Priority Data**

Sep. 22, 2003 (JP) 2003-027638

(51) **LOC (7) Cl. 14-01**

(52) **U.S. Cl. D14/205**
